United States Patent Office

Des. 180,141
Patented Apr. 23, 1957

180,141

SOFA

Morris Futorian, Glencoe, Ill.

Application March 28, 1955, Serial No. 35,227

Term of patent 7 years

(Cl. D15—11)

Fig. 1.

Fig. 2.

Fig. 1 is a front perspective view of a sofa, showing my new design.

Fig. 2 is a top view thereof.

The back of the sofa is substantially plain.

I claim:

The ornamental design for a sofa, as shown and described.
